M. H. DAVIS,
ELECTRIC LIGHT SOCKET.
APPLICATION FILED DEC. 3, 1919.

1,411,002.

Patented Mar. 28, 1922.

Inventor.
Marvis H. Davis.

UNITED STATES PATENT OFFICE.

MARVIN H. DAVIS, OF DOUGLAS, ARIZONA.

ELECTRIC-LIGHT SOCKET.

1,411,002.

Specification of Letters Patent. Patented Mar. 28, 1922.

Application filed December 3, 1919. Serial No. 342,102.

To all whom it may concern:

Be it known that I, MARVIN H. DAVIS, citizen of the United States, residing at Douglas, in the county of Cochise and State of Arizona, have invented certain new and useful Improvements in Electric-Light Sockets, of which the following is a specification.

10 This invention relates to an improved electric light socket and has as one of its principal objects to provide a device of this character wherein a circuit through the socket may, by simply pulling upon a lamp carried thereby, be closed for energizing the lamp.

The invention has as a further object to provide a socket wherein the lamp may, by simply pulling thereon, be also extinguished.

20 A further object of the invention is to provide a socket employing a base formed of sections slidably connected for operating a switch and wherein by shifting one section with respect to the other, the switch may be either opened or closed.

25 And the invention has as a still further object to provide a socket which will be neat and attractive in appearance and wherein all of the working parts will be enclosed within the casing employed.

30 Other and incidental objects will appear hereinafter.

In the drawings:

Figure 1 is a side elevation of my improved socket, the casing and insulating sleeve being shown in section,

35 Figure 2 is a side elevation showing the socket with the casing removed,

40 Figure 3 is a view similar to Figure 2 but particularly illustrating the mounting of the switch of the socket,

Figure 4 is a bottom plan view of the device.

Figure 5 is a perspective view showing the switch in detail, and

45 Figure 6 is a detail perspective view of the ratchet employed for actuating the switch.

50 In carrying the invention into effect, I employ, in constructing my improved socket, a base which is formed of sections 10 and 11 respectively. These sections are in the nature of disks of insulating material and standing from the section 10 adjacent opposite sides thereof are posts 12. These posts

extend through the section and, at their lower end portions, receive nuts 13 confronting opposite side faces of the section for firmly securing the posts in vertical position. At their upper ends, the posts are formed with heads 14 which are normally received in suitable sockets in the lower face of the section 11 of the base. Depending from the section 11 are arms 15 provided at their lower end portions with laterally directed terminals 16 slidably receiving the posts therethrough. One of said arms is secured to the section 11 by a binding post 17 engaging through the section while the other arm is secured to said section by a screw bolt 18. As will be clear, the section 10 is thus slidably connected with the section 11 and bearing between the heads 14 of the posts 12 and the terminals of said arms are helical springs 19 surrounding the posts and acting to retract the section 10 and hold the section in normally retracted position. Connected to the section 10 is a threaded shell 20 provided at its upper end with laterally directed lugs having the lower ends of the posts 12 engaged therethrough so that the shell is thus held by the lowermost of the nuts 13 upon the posts and mounted upon the lower end portion of one of said posts within the shell is a contact 21, this post and contact being insulated from the shell. The shell is of course, designed to receive a lamp, as indicated in dotted lines at 22, to cooperate with this contact. Surrounding the base and shell is an insulating sleeve 23 and enclosing said sleeve is a casing 24 closed at its upper end by a removable cap 25. As will be best observed upon reference to Figure 1, the section 10 of the base as well as the shell 20 are freely received within the lower end portion of the sleeve so that these parts may readily shift within the sleeve.

55 Mounted upon the lower side of the section 11 of the base is a yoke 26 held by a screw bolt 27 and a binding post 28 engaged through the section. Journaled upon the arms of said yoke is a switch shaft 29 and fixed upon said shaft adjacent one end thereof is a switch contact 30. Extending beneath this contact for engagement thereby is a fixed spring contact 31 secured at its upper end to the section 11 of the base by the screw bolt 18. Secured at one end by the

- screw bolt 27 is a flat spring 32 rebent to engage at its free end with the switch contact, the free end of said spring being formed with lateral lugs to bear against the contact.
- 5 Fixed upon the shaft adjacent the end thereof opposite the switch contact is a ratchet disk 33. As particularly shown in Figure 6, this disk is formed from a piece of sheet metal slit at spaced points along radial lines 10 to provide a plurality of segmental ratchet teeth slightly twisted axially so that the corresponding edges of said teeth extend laterally at the inner side of the disk. Freely mounted upon the shaft to coact with the 15 disk 33 is a rotatable ratchet disk 34 cut away at its inner side to provide a plurality of segmental ratchet teeth adapted to cooperate with the ratchet teeth of the disk 33 and bearing between the disk 34 and the switch 20 contact 30 is a helical spring 35 surrounding the shaft 29 and tensioning the disk 34 against the fixed disk. Pivottally connected at one end to the disk 34 at a point adjacent its periphery is a link or pitman 36, the opposite end of which is secured to the section 25 10 of the base by a pin or other approved fastening device 37.
- In practice, circuit wires are connected to the binding posts 17 and 28 so that current 30 will be supplied through the post 17, the adjacent arm 15 and post 12 to the contact 21. The fixed contact 31 has, through the other post 12 and arm 15, ground connection with the shell 20 while the binding post 28 is in 35 circuit with the switch contact 30 through the yoke 26 and shaft 29 as well as through the tensioning spring 32. Thus, assuming the parts to be in the position shown in Figures 1, 2 and 3 of the drawings, the lamp 22 40 may be grasped when, by pulling downwardly thereon, the section 10 of the base will be shifted away from the section 11. Thus, the ratchet disk 34 will, through the link 36, be caused to turn the disk 33 and 45 consequently the shaft 29 a quarter turn, so that the switch contact 30 will be moved into vertical position engaging the fixed contact 31 for closing the circuit through the lamp. Upon the release of the lamp, the tensioning 50 spring 32 will prevent counter-rotation of the shaft so that the ratchet disc 34 will consequently ride over the disk 33 as the section 10 is retracted by the springs 12. Consequently, the switch will remain closed until 55 the lamp is again pulled downwardly when, as will be readily appreciated, the ratchet disk 34 will again cooperate with the disk 33 for moving the switch contact 30 to the position shown in the drawings out of engagement with the contact 31 to open position, when the lamp will be extinguished. It will accordingly be seen that I provide a 60 socket wherein the lamp may be lighted or extinguished by simply pulling downwardly

thereon and while I have indicated that the 65 lamp itself is grasped for operating the switch of the socket, still, I do not wish to be limited in this regard as any approved means may be provided within the spirit of the invention for shifting the section 10 of the 70 base of the socket relative to the section 11 to operate the switch. For instance, the shade of the lamp may be grasped, or the socket, and the switch thus operated while by suitably attaching a cord, pull upon the cord 75 will serve to actuate the switch. Further, by removing the shell 20, attaching a lamp cord to the posts 13 and supplying a suitable casing and base, the switch may be used in a rosette. Also it may be placed between 80 rosette and socket and by employing a suitable base in lieu of the cap 25, the switch may be made into a receptacle.

Having thus described the invention, what is claimed as new is:

85

1. An electric light socket including a sectional base, means connecting said sections whereby one section may be shifted relative to the other, a yoke upon one section, a shaft journaled upon said yoke, a switch contact 90 carried by said shaft, a ratchet disk fixed to the shaft, a ratchet disk free on the shaft and adapted to cooperate with the first disk, and a connection between the latter disk and the movable section of the base whereby the 95 switch contact will be turned to open and closed position respectively when the movable section is shifted.

90

2. An electric light socket including a sectional base, means connecting the sections of 100 the base whereby one section may be shifted relative to the other, a rotatable shaft carried by one section, a switch contact fixed to said shaft, a ratchet disk fixed to the shaft and provided with teeth at one side thereof, 105 a ratchet disk free on the shaft and provided at one side with teeth to cooperate with the teeth of the fixed disk, yieldable means tensioning the movable disk against the fixed disk, yieldable means holding the shaft 110 against counter-rotation, and a link extending between the movable section of the base and the movable ratchet disk whereby the switch contact will be rotated to open and closed position respectively when the movable section is shifted.

110

3. A device of the character described including a sectional base, and yieldable means including abutment members between the sections normally holding said sections in 120 spaced relation and permitting relative reciprocation thereof, a yoke upon one of said sections, a shaft journaled upon said yoke, a metallic block fixed upon the shaft and having two narrow and two wide flat sides, a 125 ratchet disc fixed to the shaft, a second ratchet disc free on the shaft, a link forming an operative connection between said free

125

disc and the other of said sections, a spring surrounding the shaft to bear between said block and the free disc, holding the discs in engagement, whereby when the last mentioned section is reciprocated, the shaft will be rotated turning said block, a spring bearing between the yoke and said block adapted

to co-operate with the flat sides thereof for yieldably locking the shaft, and a contact mounted to co-operate with the narrow sides of said block.

In testimony whereof I affix my signature,

MARVIN H. DAVIS. [L.S.]
